H. C. JOHNSON AND E. H. PERCY,
PROTECTING DEVICE FOR STEAM TURBINE BLADES,
APPLICATION FILED MAY 29, 1917, RENEWED DEC. 24, 1919.

1,333,661.

Patented Mar. 16, 1920.

UNITED STATES PATENT OFFICE.

HANS C. JOHNSON AND EDWIN H. PERCY, OF FORT BRAGG, CALIFORNIA.

PROTECTING DEVICE FOR STEAM-TURBINE BLADES.

1,333,661.

Specification of Letters Patent. Patented Mar. 16, 1920.

Application filed May 29, 1917, Serial No. 171,672.

Renewed December 24, 1919. Serial No. 347,199.

To all whom it may concern:

Be it known that we, HANS C. JOHNSON and EDWIN H. PERCY, citizens of the United States, and residents of Fort Bragg, in the county of Mendocino and State of California, have invented a certain new and useful Improvement in Protecting Devices for Steam-Turbine Blades, of which the following is a specification.

10 Our present invention relates generally to steam turbines, and more particularly to protecting means for the blades at the low pressure end of the bladed cylinder, our object being the provision of a protecting device capable of effective and efficient use without detracting from the power and efficiency of the turbine as ordinarily utilized.

20 In explaining our improvements, it has been found from experience that when, in certain types of turbines the condenser pump fails for any reason to clear the water from the exhaust pipe, the backing up of the water therein having free access to the swiftly moving blades of the turbine adjacent its low pressure end, said blades are invariably stripped, bent, or otherwise so damaged and to such an extent from such contact with the water that the turbine has to be shut down and new blades installed, 30 involving a considerable loss of time and expense as well as great annoyance.

35 In carrying out our invention we provide means capable of ready installation in connection with a turbine cylinder at the low pressure end thereof, the action of which in use is to throw off any backed up water and continually force the same away from the adjacent cylinder blades and out of contact therewith, at the same time providing for substantially unrestricted passage of the 40 steam to the exhaust so as to avoid interference with the ordinary functions of the turbine or decrease of its normal efficiency.

45 In the accompanying drawings illustrating our invention:

Figure 1 is a sectional view through a portion of a steam turbine of the type to which our invention is applied, illustrating the relative position of the protecting means provided thereby;

Fig. 2 is an end view of the turbine cylinder provided with our improvements, looking at the low pressure end thereof;

50 Fig. 3 is a side view of a portion of the low pressure end of the cylinder with our

invention partly broken away and in section, and

Fig. 4 is a diagram illustrating the relative engagement of the stationary and moving blades and protecting member provided by our invention.

Referring now to these figures, and more particularly to Fig. 1, the turbine cylinder is seen generally at 10, the fast moving blades 11 of which, adjacent its low pressure end, are normally subject to the action of water backed up in the exhaust 12, and unprotected as against contact therewith.

Our invention contemplates the connection of means to the low pressure end of the cylinder 10, which will protect the fast moving blades 11 and obviate their contact with water backed up in the exhaust 12, and to this end provides a circular plate 13, the inner hub portion 14 of which is solid to a point adjacent and slightly beyond the periphery of the cylinder 10, and is bolted by annular bolts 15 to the low pressure end of said cylinder, as particularly seen by reference to Figs. 2 and 3, the relation of this blade 13 with the surrounding members of the turbine being plainly seen from Fig. 1.

The plate 13 has an annular series of radially slotted openings 16 cut therethrough at an angle of substantially forty-five degrees and falling away angularly toward the moving blades 11 in the direction of movement of the latter, as plainly seen by reference to Fig. 4, in which the blades 11 appear in their operative position between series of stationary blades 17, the annular edge of the plate 13 being left with the arm 18 sufficiently heavy to protect and support the webs 19 between slots 16.

Thus, falling away as they do toward the moving blades at the angle stated and in the direction of rotative movement of the blades of the cylinder 10, the annular series of slots 16 provide for unrestricted passage of the steam to the exhaust, and the webs between these slots provide for an effective and efficient discharge of any backed up or accumulated water away from the blades 11, so as to obviate contact of the blades therewith and consequent injury of the blades for the reasons first above stated.

We claim:

1. In a turbine, the combination with the turbine cylinder having its low pressure end adjacent the exhaust, of a protecting plate

secured to and moving with the low pressure end of the cylinder, having an annular series of inclined slots adjacent the low pressure cylinder blades, the webs between which 5 slots act to discharge accumulated water away from the cylinder during rotation thereof.

2. In a turbine, the combination with the rotating turbine cylinder, of a protecting 10 plate secured to the low pressure end thereof and rotating therewith, said plate having an annular series of radially disposed slots inclined with respect to the axis of the cylinder, and inclined webs between which slots 15 act to normally force the accumulated water away from the cylinders.

3. In a turbine, the combination with the 20 turbine cylinder, of a protecting plate secured to the low pressure end of the cylinder to rotate therewith, said plate having an inner hub portion bolted to the adjacent cylinder end and having an outer solid rim, and an annular series of radially extending slots 25 between its head and rim portions, extending

through the plate at angles inclined with respect to the axis of the cylinder, for the purpose described.

4. In a turbine, the combination with the rotating turbine cylinder, of means adjacent the low pressure end thereof arranged 30 to provide for unrestricted passage of steam to the exhaust and at the same time prevent contact of the turbine blades with the water backed up in the exhaust, at the adjacent end of the cylinder.

5. In a turbine, the combination with the rotating turbine cylinder, of means adjacent the low pressure end thereof arranged to provide for unrestricted passage of steam to the exhaust and at the same time prevent 40 contact of the turbine blades with the water backed up in the exhaust, at the adjacent end of the cylinder, said means being connected to and rotating with the said cylinder.

HANS C. JOHNSON.
EDWIN H. PERCY.
